UNITED STATES PATENT OFFICE.

ALVIN W. CHORMANN, OF WASHINGTON, PENNSYLVANIA.

STATION-INDICATOR.

SPECIFICATION forming part of Letters Patent No. 501,477, dated July 11, 1893.

Application filed September 28, 1892. Serial No. 447,103. (No model.)

To all whom it may concern:

Be it known that I, ALVIN W. CHORMANN, a citizen of the United States of America, residing at Washington, in the county of Washington and State of Pennsylvania, have invented certain new and useful Improvements in Indicators, of which the following is a specification, reference being had therein to the accompanying drawings.

10 This invention relates to indicators for railway cars and consists in certain improvements in the construction of the same, as hereinafter described and claimed.

In the accompanying drawings—Figure 1 represents a perspective view of an indicator provided with my improvements. Fig. 2 is a vertical section taken on line $x-x$ of Fig. 3. Fig. 3 is a front view of the indicator, certain parts being removed. Fig. 4 illustrates the 20 ratchet mechanism employed and other details. Fig. 5 illustrates a locking latch and other details employed in connection therewith. Fig. 6 further illustrates the ratchet mechanism.

25 A designates the casing of the indicator which is provided with a front door having openings in which plates of glass are set through which the words and figures on the indicating apron may be seen. Within the 30 casing A are journaled, in suitable bearings, a rotative shaft B, a roller C, above said shaft, and a roller D, below said shaft. On one end of the central shaft B is mounted a gear-wheel E and on the extended journals of the rollers.

35 C and D are mounted respectively the pinions a and b . As seen in Fig. 3, the journal of roller D is extended farther than the journal of the upper roller C, and the pinion b is not on the same vertical line with the pinion a ; the gear wheel E, however, may be put in connection with either of said pinions by a longitudinal movement of the shaft B as hereinafter set forth. The opposite end of the 40 shaft B is extended through the casing A and is provided with a finger piece L, by means of which the shaft may be turned by hand, or may be moved lengthwise so as to bring the gear-wheel E in connection with the lower pinion b or with the upper pinion a . Notches or 45 grooves c are made in the shaft B to receive a sliding catch d by means of which said shaft may be secured in the position to which it 50 may be adjusted. Two small rollers F and G

are journaled in suitable bearings, in position in front of the larger rollers C and D.

H indicates an apron which is connected at one end with the roller C and from thence is passed about the two rollers F and G and then connected with the roller D, the apron being so applied that it may be wound upon either of the rollers C, D, and at the same time drawn from the other. On the apron H are marked the changeable, indicating words and figures, and the movements of said apron are effected by the following described mechanism.

On the extended shaft B is a ratchet wheel f and pivotally connected with said shaft is a yoke e which carries a number of spring pawls i in position to connect with wheel f . 70 These pawls i are of different lengths—see Fig. 6—so that, at least, one of said pawls will connect promptly with the ratchet f . The yoke e is connected by a double connecting rod m with the lower end of an elbow lever I, pivoted in the top of the casing A, a guard l serving to keep the rod m in position. A circular disk p is fast on a journal of the roller C and has two projections r located at opposite points on the disk. A locking latch o is pivoted in position to connect with the disk p and a catch n extends from the rod m , in position to engage the latch when the rod moves downward. The said latch o has a tongue s , 80 for connection with the projections r severally, and a lip v to strike the edge of the disk p when the latch descends.

The latch o is usually held in its raised position by the catch n as seen in Fig. 3, and when it is desired to make a movement of the apron H and thus change the indicator, this is done by drawing a cord t attached to the elbow-lever I, whereby the connecting rod m is drawn upward, thus effecting, through the yoke e and ratchet mechanism, a partial 90 rotation of the shaft B; this movement being communicated from said shaft, through gearing, to the rollers on which the apron H is mounted, a movement of the latter is produced, and at the same time the latch o is released from the catch n on the rod m and said latch closes by gravity on the disk p , the tongue s of the latch coming in position to stop the rotation of the rollers by the contact of one of the projections r with said 95 tongue. The parts are so constructed that 100 105

the rotation of rollers C, D is stopped when said rollers have made about one half of a revolution, that being sufficient to produce the required movement of the apron H. A 5 retracting spring *q* is connected with the lower end of rod *m* and serves to draw down the rod to its former position and raise the latch *o* from the disk *p*. The shaft B, being adjustable endwise, may be shifted from its 10 connection with either of the rollers C, D, to the other roller, the said shaft being moved lengthwise so that the gear-wheel E is moved out of connection with one of the pinions *a*, *b*, and into connection with the other pinion; 15 such shifting being for the purpose of changing the direction of the movement of the apron H on the rollers.

A short sleeve *u* is placed loosely on the shaft B and serves to keep the yoke *e* and 20 ratchet mechanism in place.

J and K indicate two aprons which are mounted on rollers journaled in the lower part of the case A at the front, said aprons being intended to bear the names of stopping 25 places on the route. Finger pieces *y* are formed on the journals of these rollers so that the latter may be turned by hand.

I claim—

1. The combination, with a casing, of a ro-

tative shaft journaled therein, a series of rollers with shafts connecting therewith by spur gearing, a ratchet and pawl connected with said shaft, a connecting rod having a catch fastened thereto, a disk, provided with projections and connected with one of said rollers, a pivoted latch, in position to connect with said disk and with the catch on said connecting rod, and a pivoted hand-lever, substantially as set forth for the purposes described.

2. The combination with a rotative shaft, adjustable lengthwise, of a yoke and ratchet mechanism connected with said shaft, a series of rollers and gearing, a disk connected with one of said rollers and provided with one or more projections *r*, a rod connected with said ratchet mechanism and with a pivoted lever, a catch on said connecting rod, and a pivoted latch in position to connect with said catch and with said disk, substantially as set forth and described.

In testimony whereof I have affixed my signature in presence of two witnesses.

ALVIN W. CHORMANN.
